UNITED STATES PATENT OFFICE.

DAVID SCHOENTAG, OF GLASCO, AND ELMER J. LATUS, OF ALBANY, NEW YORK.

LIQUID-HYDROCARBON DISTRIBUTER FOR ROADS.

1,114,919.

Specification of Letters Patent.

Patented Oct. 27, 1914.

Application filed October 10, 1911. Serial No. 653,937.

To all whom it may concern:

Be it known that we, DAVID SCHOENTAG and ELMER J. LATUS, citizens of the United States, and residents of Glasco, Ulster county, State of New York, and Albany, county of Albany, State of New York, respectively, have invented certain new and useful Improvements in Liquid-Hydrocarbon Distributers for Roads, of which the following is a specification.

This invention relates to a wheeled-tank device for distributing liquid upon a surface or region traveled over.

The device is designed more particularly for use in distributing liquid asphalt or the like over crushed stone beds in road-building, or oil on top of the finished road to bind the surface together.

One of the objects of the invention is, in a simple, low-cost, one-man device, adapted for operation by unskilled labor, to provide convenient and reliable means for opening and holding open the valve mechanism controlling the discharge of the tank.

A further object is to provide an improved form of discharge comprising two chambers, controlled by separate valves and having discharge openings of different sizes, whereby streams or sheets of the liquid of different, fixed thickness may be permitted to flow from the device, according to which valve or set of valves is opened; in this way doing away with the necessity for adjustment of a single discharge opening, in order 35 to secure variation in the quantity of liquid distributed within a given time.

A further object is to provide protection for the valves and to prevent impurities or clogging matter from entering the valve 40 openings, by means of a suitable capacious chamber containing the valves and having an open side communicating with the main interior of the tank and guarded by a removable strainer.

Further objects of the invention will become apparent as the specification proceeds.

With these objects in view the invention consists in certain improvements, parts and combinations, the preferred embodiments of 50 which are illustrated in the accompanying drawings which are hereby made a part of this specification.

In the said drawings:—Figure 1 is a top plan view; Fig. 2 is a partial section on the line 2—2 of Fig. 1; Fig. 3 is a front eleva-

tion; and Fig. 4 is a fragmentary sectional view showing a modified construction of valve-operating means.

In these views the numeral 10 indicates a tank, preferably of oblong rectangular shape. This tank is preferably supported by means of a pair of wheels 11, which may be mounted loosely on the ends of a rod 12, that passes loosely through a tube 13 connecting the side walls of the tank and acting as a brace therefor. The tank is provided at its rear end with two discharge chambers 14 and 15, which are located immediately below the rear part of the tank, in rear of the wheels, the bottom of the tank forming the tops of the chambers. The chambers are triangular in cross-section, being formed by downwardly-inclined, converging, front and back walls 16 and 17, and a central vertical wall 18, which extends downward from the bottom of the tank and completely divides the interiors of the chambers from each other. The end portions of the discharge chambers preferably extend beyond the wheels, and are provided with suitable end walls. The walls 16 and 17 terminate at their lower edges at unequal distances from the central wall 18, so as to afford adjacent slotted discharge openings 19 and 20, of different widths. The central wall extends downward below the front and back walls, so as to afford a depending lip from which the fluid will flow. Each discharge chamber communicates with the interior of the tank by means of one or more openings 21, 22 through the tank bottom. These openings are controlled by suitable valves 23, 24. The valves are protected by a horizontal plate or partition 25 within the tank, this partition preferably extending from side to side and to the back thereof. The capacious chamber thus formed for the reception of the valves has its open front side in communication with the main interior of the tank, and this opening is guarded by means of a removable strainer 26. This strainer occupies an inclined position, resting at its lower end against an inclined ledge 27 projecting upward from the tank bottom, and at its upper end against the forward edge of the plate 25. The strainer has a suitable handle 28 at its top, for facilitating removal. The valve-controlled openings 21 and 22 are preferably staggered with relation to each other. When this is the case horizontal

baffle plates 29 and 30 are employed in the two discharge chambers 14 and 15, to distribute the fluid evenly to the slotted discharge openings 19 and 20.

In the form of the invention shown in Figs. 1 to 3 the tank is provided at the front with two sets of handles for pulling the same. One pair of handles 31 are formed by forwardly-projecting shafts which are secured rigidly to the sides of the tank. These shafts are so arranged that a man may walk between them comfortably with one hand grasping each handle, in the position indicated by dotted lines at A in Fig. 2. The second pair of handles for pulling the tank are pivotally connected with the tank, and have connections with the valves 23 and 24, whereby the changed relation between these handles and the tank when the latter is drawn by means of the former causes the valves to open and remain open. In the construction illustrated the handles 32 are normally at a different elevation from the handles 31, so that the handles 32 must be moved in order that the operator may draw the tank conveniently by means of them. This movement of the handles results in the opening of the valves. The handles 32 consist of bulb-shaped grips, which are pivoted at 33 to brackets secured to the forward ends of the handle shafts 31. These handles normally project downward, and are swung upward to the position indicated by dotted lines at B when the operator grasps them for the purpose of pulling the vehicle. The handles 32 have right angular extensions 34, to which are pivoted the forward ends of links 35. These links extend rearward to points adjacent to the front of the tank and are pivoted at their rear ends to the lower ends of cranks 36 which are secured to a rock shaft 37 journaled in hangers or brackets in front of the tank on the handle shafts 31. A central upward-extending curved lever arm 38 is secured to the rock shaft 37, and is connected by a link 39 with the forward end of a valve-lever 40 within the tank. This lever 40 is in the nature of a frame approximating in width the interior of the tank, so that the interior of the tank is not obstructed. It is pivoted intermediate its ends on a rod or shaft 70, which is secured endwise to the sides of the tank and serves to brace the same. The rear end of the frame-like lever is formed by two bars 41, 42, to which may be connected the valve stems 43, 44. Either valve or set of valves may be disconnected from the lever by removing the pins 45 which pass through registering openings in ears 46 on the bars and in the upper ends of the valve stems. The valve stems are guided in openings in the plate 25 and also in openings in braces 47. The lower ends of the valve stems are connected loosely with the valves 23 and 24, so

as to facilitate the action of the valves in finding their seats.

A spring 53 is provided for restoring the parts and closing the valves 23 and 24. This spring may be placed at different points, but is illustrated as connected at one end to a lug 54 on the lever arm 38 and at the other end to the front of the tank.

The device is preferably provided beneath the tank with a fire chamber 48 having a hinged door 49, and a chimney 50 extending upward through the tank. The tank is preferably provided with two hinged covers 51 and 52. These features are disclosed in our prior Patent No. 1,028,288 dated June 4, 1912.

A gage 65 is provided at the front of the tank 10, in alinement with the outer end wall of the discharge chambers 14 and 15. By means of this gage the operator is enabled to guide the device along the margin of a previously oiled strip. A bracket 66 which is clamped by a set-screw 67 onto the shaft-handle 31 holds at its outer end the said gage-rod 65 in vertical adjustment by means of a set-screw 68.

In operation, when it is desired to pull the tank with the valves closed, the operator takes his position between the shafts and grasps the handles 31. When it is desired to open the valves and to draw the tank with them held open, the operator shifts his grasp from the handles 31 to the handles 32. The position of the handles 32 necessitates their being swung upward by the operator in order to pull the tank in a normal manner. This movement results in the opening of the valves 23 and 24. The changed positions of the various pivotal connections is indicated by solid circles in Fig. 2. The movement of the handles 32 is limited by any suitable means, such as the lever arm 38 abutting against the forward edge of the tank. This operation places the spring 53 under tension, so that the spring restores the parts and closes the valves when the operator releases his grasp upon the movable handles 32. The fluid may be discharged from either or both of the discharge orifices 19 and 20. For the first spreading upon the stone the valve 23 is disconnected from the lever 40, so that the chamber 14 is cut off from the interior of the tank, and the discharge is only through the wider slot 20. For the top coating the valve 24 is disconnected from the lever 40, so that a thinner stream is discharged through the slotted orifice 19. When the valves of both chambers are opened, a stream of maximum thickness is allowed to flow through the two adjacent slotted discharge openings. If desired, one or both of the slotted openings might be regulated by a slide, 71, and as disclosed in our prior application aforesaid. When the operator

grasps the handles 32 to draw the tank and open the valves, the forward and heavier part of the tank tilts downward to a certain extent. For this reason the bottom of the tank is inclined downward and rearward, so that the contents will always find their way to the discharge chamber at the rear. Whether the tank actually tilts or not when the handles 32 are grasped, the overbalancing of the tank at one side of the axle assists in holding the valves open.

In the form of the invention shown in Fig. 4 the shafts 31^a, which afford handles at their forward ends, are pivoted to the front of the tank at 60. The rear ends of the shafts are connected with the valve lever 40 by means of the link 61, which is pivoted at opposite ends to the shafts and to the lever 40. The shafts 31^a are normally locked against pivoting by means of a pivoted catch 62, which engages with the pivot rod 63. When this catch is released, the part of the tank in advance of the axle sinks by reason of being overbalanced, and this movement results in the opening of the valves. A stop 64 limits the extent of relative movement between the tank and the shafts 31^a.

Having described our invention, what we desire to secure by Letters Patent and claim is:—

1. In a device of the character described, the combination of a wheeled tank having a discharge, valve means for controlling the discharge, handles in front for pulling the tank, said handles being pivotally connected with the tank, and connections between the handles and the valve means, whereby the relation between the handles and tank resulting when the latter is pulled by the handles which are free to pivot, causes the opening of the valve means.

2. In a device of the character described, the combination of a wheeled tank having a discharge, valve means for controlling the discharge, handles in front for pulling the tank, said handles being movably connected with the tank, and means operated by said handles for opening said valve means.

3. In a device of the character described, the combination of a wheeled tank having a discharge, valve means for controlling the discharge, handles in front of the tank for pulling the same with the valves closed, a second set of handles in front of the tank for pulling the same with the valves open, these handles being movably connected with the tank and being positioned so that the operator may readily shift his grasp from one set of handles to the other so as to pull the tank by means of either, and connections between the second set of handles and the valve means whereby the latter are opened by the change in relative position

between these handles and the tank when the tank is pulled thereby.

4. In a device of the character described, the combination of a wheeled tank having a discharge, valve means for controlling the discharge, shafts extending in front of the tank and affording handles for pulling the same with the valves closed, a second pair of handles pivoted to said shafts, these handles being so constructed and arranged that the operator may shift his grasp from one set of handles to the other to pull the tank by either, and connections between the second set of handles and the valve means for opening the latter.

5. In a device of the character described, the combination of a tank supported on two wheels and having a discharge, valve means for controlling the discharge, handles in front for pulling the tank, said handles being pivotally connected with the tank, and connections between the handles and the valve means, whereby the relation between the handles and tank resulting when the latter is pulled by the handles which are free to pivot, causes the opening of the valve means, said tank being overbalanced at one side of its wheels so as to hold the valve means open.

6. In a device of the character described, the combination of a wheeled tank having a discharge at the rear, valves for controlling the discharge, shafts extending in front of the tank and affording handles for pulling the same with the valves closed, a second pair of handles pivoted to said shafts, an intermediate lever at the front of the tank, links connecting the pivoted handles with said lever, a frame-like lever within the tank leaving the interior thereof unobstructed, a link connecting said lever with the intermediate lever, and connections between said frame-like lever and the valves.

7. In a device of the character described, the combination of a wheeled tank, a discharge chamber beneath the tank at the rear thereof having communication with the interior of the tank, a valve in the tank controlling said communication, a valve stem and an open frame-like operating lever, a plate extending from the sides and rear of the tank over the valve, and through which the valve stem passes, and a strainer supported in an inclined position with its lower end against a ledge on the bottom and its upper part against said plate, said strainer being removable from between the members of the frame-like lever.

8. In a device of the character described, the combination of a wheeled tank having a discharge valve, means for controlling the discharge, handles in front for pulling the tank, said handles being operatively connected up with the tank and valve and having a movement relatively to the tank so that when the tank is pulled the handles are

moved relatively thereto to cause the opening of the valve and a spring for restoring the handles and closing the valve.

9. In a device of the character described, 5 the combination of a wheeled tank having a discharge, valve means for controlling the discharge, handles for pulling the tank with the valve closed, a second set of handles operatively connected up with the tank and 10 normally in a position different from that of the first set of handles, but being so positioned that the operator may readily shift his grasp from the first set of handles to the second set to pull the tank by means of the 15 latter, thereby operating the second set of handles, and connections between the second set of handles and the valve means whereby the operation of the former opens the valves.

10. In a device of the character described, 20 the combination of a wheeled tank having a discharge, valve means for controlling the discharge, shafts extending in front of the tank and affording a set of handles for pulling the same with the valves closed, a second 25 set of handles connected to said shafts and projecting therefrom, said sets of handles being so constructed and arranged that the operator may readily shift his grip from one set to the other to pull the tank by either set, 30 and connections between the second set of

handles and the valve means whereby the pulling of the tank by these handles opens the valve means.

11. In a device of the character described, 35 the combination of a wheeled tank having a discharge at the rear, a valve for controlling the discharge, shafts extending in front of the tank and affording handles for pulling the same with the valve closed, a second set of handles operatively connected to said 40 shafts, being so constructed and arranged that the operator may readily shift his grip from one set of handles to the other to pull the tank by either, a substantially upright lever at the front of the tank, links connect- 45 ing the second set of handles with said lever, a substantially horizontal intermediately-pivoted lever extending lengthwise of the tank, being connected at its rear end to the valve, and a link connecting the forward end of 50 this lever with the upright lever.

Signed in the city and county of Albany and State of New York, this 29th day of September, A. D. 1911.
